UNITED STATES PATENT OFFICE.

OTTO E. EDSTROM, OF CHICAGO, ILLINOIS, ASSIGNOR TO ILLINOIS PATENTS CORPORATION, OF CARY, ILLINOIS, A CORPORATION OF ILLINOIS.

AUTOMATIC STOP ROLLER FOR SHADES.

Application filed January 15, 1923. Serial No. 612,579.

To all whom it may concern:

Be it known that I, Otto E. Edstrom, a citizen of the United States, and a resident of the city of Chicago, in the county of Cook and State of Illinois, have invented certain new and useful Improvements in an Automatic Stop Roller for Shades; and I do hereby declare that the following is a full, clear, and exact description of the same, reference being had to the accompanying drawings, and to the numerals of reference marked thereon, which form a part of this specification.

This invention relates to shade rollers of the type in which a helical driving member moves a driven member lengthwise of the roller, and the stopping point is determined by the arrival of the traveler at the end of its longitudinal movement. The present invention is an improvement over the device shown in my Patent No. 1,303,182 for an "Automatic stop for window shade rollers," granted May 6th, 1919. One characteristic difference between the present invention and said patent is that in the patent the automatic stop is a separate article of manufacture and is attached to the roller when desired, while the present invention contemplates a roller in which the stop mechanism is within and constitutes a part of the roller itself and is sold with the roller as one article.

It is an object of this invention to build a roller with the stop mechanism and rewind mechanism all within one end of the roller, so that the user can cut the roller to the needed length without being obliged to make allowance for the space occupied by the stop mechanism or otherwise pay attention thereto. Moreover, the end of the roller which he so cuts is provided with the ordinary cap supplied with a round pivot so that the user does not need to use care to place a cap supplied with a non-rotative projection in the correct position relative to the non-rotative projection at the other end of the roller.

It is a further object of this invention to provide a roller in which the rewind spring is always under tension instead of said spring being permitted to unwind, even

when the roller is released from the fixtures. It is true that the usual type of roller can be removed from the fixtures without releasing the rewind spring if care is taken to keep the pawls of the ratchet device engaged, but in this invention the pawls may disengage without letting the rewind spring relax.

It is a further object of my invention to provide an arrangement of rewind mechanism, stop mechanism and roller wherein the alignment of the parts is obtained by the manufacture and not left to the man who fits the roller to its particular window.

It is a further object of my invention to make a mechanism of the class described which shall be less expensive to manufacture. This I accomplish by, among other things, doing away with all extra housings and instead providing space for the stop mechanism by making the bore for the rewind mechanism extend further than said rewind mechanism alone requires.

It is a further object of my invention to avoid requiring the man who fits the roller to its individual window to perform any difficult or accurate mechanical operation.

It is a further object of my invention to use one shaft both for the rewind mechanism and for the stop mechanism.

It is a further object of this invention to so arrange the various parts of the mechanism that stop mechanism may be placed in the extreme inner end of the recess in the roller.

Other and further important objects of this invention will be apparent from the disclosures in the specification and the accompanying drawings.

The invention (in a preferred form) is illustrated in the drawings and hereinafter more fully described.

On the drawings:

Figure 1 is a longitudinal section.

Figure 2 is a view partly in elevation and partly in section showing a modification.

Figure 3 is a similar view showing another modification.

Figure 4 is a detail showing the structure of a fastening used in the modification shown in Figure 2.

Figure 5 is a section upon the line 5—5 of Figure 1.

Figure 6 is a section upon the line 6—6 of Figure 1.

5 As shown on the drawings:

The roller has the usual cylindrical body 19 with a long concentric bore 11 in one end thereof. The bore contains a shaft 12, to which is fastened the usual fixture member 13 projecting beyond the end of the roller and intended to cooperate with the usual curtain fixture to prevent rotation of the shaft 12. The fixture member 13 may be secured to the shaft 12 in any desired way but I prefer to cut a slot 53 in the end of the shaft 12 extending from one side of the shaft beyond the axis thereof. I then insert the shank of the member 13 into this slot with its edge bearing against the bottom of the slot. The member is then secured in place by a pin 55 extending through the shaft 12.

The end of the shaft 12 which contains the fixture member 13 may be capped by a ferrule 14 of the ordinary thimble form, as illustrated in Figure 1, but when a metallic shaft is used no ferrule is needed. This ferrule serves as a bearing for a spring anchorage 15, which is preferably in the form of another thimble set over the ferrule 14 and having ears 16 extending round one or more turns of the spring 17. The end of the spring is hooked on one of these ears, as shown at 18 in Figure 5. The ears 16 are set in recesses in the wood and are turned towards the end of the roller and pass through a plate 19 which is provided with slots to receive them. The ends of the ears are then bent flat against this plate, thus securing the parts together. The plate 19 is provided with an upstanding flange 20 which serves to space the finishing thimble 21 away from the plate 19. The skirt of the finishing cap 21 extends down over the outside of the roller and is secured thereto in any well-known manner, for example, by indentations 22. In the space between the plate 19 and the plate 20 are mounted the usual ratchet pawls and the corresponding detent wheel, which are of standard construction and need not be described. The ears 16 being in notches in the wood prevent the anchorage 15 from rotating relative to the roller. Consequently the end of the spring 17 nearest the end of the roller is rotated with the roller. The other end of the spring is inserted, as shown at 23, into a slot 24 in the stationary shaft 12. Preferably this end 23 is closely adjacent the end of the slot, as is indicated by the shoulder 25 of Figure 1.

Surrounding the slotted part of the shaft 12 is a helix 26 of spring wire. One end of this helix terminates in a straight piece 27 by which the helix is anchored in a block 28. In the preferred form, the end of this

wire is carried through the block 28 and bent against the end thereof and fastened by a staple 43. The block 28 is fastened in any desired manner, for example, by a brad 54. The other end of the helix 26 is provided with a hook 42 which acts as a yielding stop for the link 30.

In the modification shown in Figures 2 and 4, the thimble 14' on the end of the stationary shaft 12 is provided with hooks 35 by which the end of the spring 17' is secured. Thus the end of the spring nearest the fixture in Figure 2 is secured not to the rotating roller but to the stationary shaft. The other or inner end of the spring must therefore be secured, not to the shaft but to the roller. This requires that the spring 17' be wound in the opposite direction to the spring 17. A block 36 is provided, to which the end 37 of the spring 17' is secured, preferably by means of a straightened end of the spring itself. This block is made with a bore 38 to accommodate the shaft 12, and it is secured to the roller in any desired way, for example, by a brad 39. The helix 26', made of spring wire, has its inner end secured to the roller, as shown at 41, and its outer or left hand end is provided with a hook 42 to serve as a limit to the outward movement of the link 30.

In the modification illustrated in Figure 3, the block 36' is made with a bore 38' large enough to accommodate not only the shaft 12 but also the straightened spring 37'. In order to prevent relative rotation between the end of this spring and the roller, the brad 39' fastens the block 36 in place and the wire of the spring 37' is fastened to the block in any desired way. This wire is continued toward the inner end of the bore 11 and formed into a helix 26'' which drives a link 30 traveling in the slot 24, but the helix 26'' is wound in the opposite way to the helix 26. The inner end of the helix 26'' is not fastened to any stationary support but terminates in a hood 42. Also the inner end of the shaft 12 in this form is not mounted in a bearing, but depends upon its bearing at the block 36' for maintenance in alignment.

In the assembly of the form shown in Figure 1, the helix 26 is first secured to the block 28 by means of the straight end 27 and the staple 43, as already explained. The link 30 is then put in place over one turn of the helix. The spring 17 is placed around the shaft 12 with the end 23 in the slot 24. The ferrule 14 and the anchorage 15 are put on the end of the shaft 12 and the fixture engaging member 13 passed through them into the slot 53 and secured by the pin 55. The other end of the spring 17 is then hooked to the ear 16. The shaft with the spring 17 thereon is then inserted into the helix 26, the link 30 being received in the slot 24, but the shaft is kept at the left of

the position illustrated in Figure 1 far enough for the ears 16 to be out of engagement with the wood of the roller.

The end of the fixture engaging member 13 is then held by a vise or other convenient means and the anchorage 15 rotated until the correct minimum tension is put into the spring 17. Then the roller is moved toward the left in Figure 1 until the ears 16 are received in the recesses in the wood. The position of these recesses about the circumference is so chosen relative to the position of the straight wire 27 that when the link 30 abuts against 27, the notches in the 15 detent disk will not be in engagement with the pawls.

Finally, the cap 21 is put on and secured as indicated at 22.

In the assembly of the modification shown in Figure 2, the procedure is similar, except that the inner and not the outer end of the spring 17' is left unfastened until the proper tension is put upon this spring. This is done by omitting the brad 49 when the block 40 is first put in place. The tension is put on spring 17' by holding the fixture engaging member 13 and rotating the roller. When the proper minimum tension is obtained, driving the brad 49 makes it permanent. The rotation is stopped when the pawls are out of engagement and driving the brad 49 with them in this position insures that the straight part 41 of the wire 26' will be in proper position relative to the ratchet 35 mechanism, except for the small changes possible by the few turns of rotation corresponding to the travel of the link 30 along the slot 24.

In the modification shown in Figure 3, the fastening for the spring 17' at the left is like Figure 4. In assembling this modification the cap 14' is left unsecured to the shaft 12 and the cap 21' omitted until by rotating the roller with the cap 14' held still (for example, by securing the flange 56 in a vise), the desired minimum tension is secured. Then the cap 14' is secured to the shaft 12 and the cap 21 put in place and fastened.

In the operation of the device in the form shown in Figure 1, the shade is attached to the roller in the usual way, rolled up and the roller put in place in the fixture. If the shade is drawn, the roller rotates in such a direction that the top side of Figure 1 moves away from observer. This causes the link 30 to travel toward the right.

The length of the helix and so the travel of the link 30 is chosen to correspond to the distance the shade is to be unrolled. Each 60 different height of window must therefore have its roller with a helix chosen to correspond to said height. Preferably the shade is made long enough to have one or two complete turns remaining on the roller when 65 the link 30 gets to the end of its travel,

When the link arrives at the straight part 27 of the wire 26, it is stopped thereby, which brings the roller to rest in a position in which neither of the pawls engages the detent disk. By slowly elevating the shade a small 70 distance the roller will rotate backwards until one of the pawls engages a notch in said disk and the shade is held in its lowered position. But, if, with the shade at its extreme downward position, it is released 75 without first being slowly elevated a small distance, the spring 17 will cause the roller to rotate relative to the stationary shaft 12 in the direction which makes the top part of Figure 1 advance from the paper. This 80 causes the link 30 to travel toward the left in Figure 1. At the end of its travel, the link 30 is caught by the hook 42. Instead of meeting a solid stop, the link meets a yielding resistance due to the fact that this hook 85 is at the end of a spring. So, even when the curtain goes up with a rush, it is brought gently to a stop, and, although the curtain goes up under the influence of the spring 17, this spring cannot unwind more than corresponds to the travel of the link 30. Even if the roller is removed from the curtain fixture bracket with the pawls disengaged from the detent disk, the spring 17 cannot 90 unwind further because the shaft 12 cannot 95 rotate relative to the roller 10 any further than the travel of the link 30 will permit.

The operation in the modification shown in Figure 2 is the same, and need not be explained in detail.

In the form shown in Figure 3, the abrupt stop of the link 30 is at the left and the yielding stop at the right. In this form therefore the pitch of the helix 26'' is in the opposite direction.

I am aware that numerous details of construction may be varied through a wide range without departing from the principles of this invention, and I therefore do not purpose limiting the patent granted otherwise than necessitated by the prior art.

I claim as my invention:

1. In a device of the character described, a shade roller having an axial recess in one end, a spindle disposed in said recess, pawl and ratchet mechanism between said roller and spindle, a rewind spring on said spindle connected thereto and to said roller, yielding stop mechanism including a helical member on said spindle connected to rotate 115 with said roller, and a traveling member driven by said roller and moving in a longitudinal slot in said spindle, said stop mechanism being located at the inner end of said spindle, the means for connecting said spring 120 and roller being so disposed with relation to the stop mechanism that when the latter reaches its extreme of movement with the shade unwound said pawl and ratchet mechanism will be out of register.

2. In a device of the character described, a shade roller having an axial recess in one end, a spindle disposed in said recess and slotted axially at its inner end, a rewind spring on said spindle connected thereto and to said roller, said spring being extended into an oppositely wound helix embracing

the inner slotted end of said spindle and rotating bodily with said roller, and a traveling stop member disposed in said spindle 10 slot and driven by said roller.

In testimony whereof I have hereunto subscribed my name.

OTTO E. EDSTROM.
